UNITED STATES PATENT OFFICE.

WILLIAM E. JEROME, OF ROCKVILLE CENTER, NEW YORK.

LIGHTING-FIXTURE.

1,350,809.

Specification of Letters Patent. Patented Aug. 24, 1920.

Application filed December 19, 1918. Serial No. 345,991.

To all whom it may concern:

Be it known that I, WILLIAM E. JEROME, a citizen of the United States, residing at Rockville Center, in the county of Nassau 5 and State of New York, have invented an Improvement in Lighting-Fixtures, of which the following is a specification.

My invention relates to lighting fixtures of the semi-indirect character employing 10 high efficiency incandescent lamps burning at high temperatures whose filaments are exceedingly bright, and its object is to direct the light upward to the ceiling and from thence over a given area and at the same 15 time to hide the filament from direct view, and blend the light diffused by the translucent bowl so that strain or injurious effect upon the eye is entirely avoided.

The details of the invention are herein- 20 after particularly described.

In the accompanying drawing:

Figure 1 is an elevation partly in section, illustrating a complete fixture embodying my invention.

Fig. 2 is a plan view of the combined reflector and shield detached.

Fig. 3 is a view illustrating the clips used in suspending the translucent bowl, and

Fig. 4 illustrates the reflector and shield 30 made of one piece of material.

Similar reference characters indicate like parts throughout the several views.

10, denotes a translucent bowl which may be supported by any suitable hangers, but I 55 prefer to employ clips 11, formed of a single piece of flat metal bent into the shape shown most clearly in Fig. 3, which fit over and under the flange of the bowl with one end bent downwardly and bearing against the inner 10 surface of the bowl, there being a loop or eye 12, bent upwardly above the rim of the bowl to receive one end of the chains 13, the other ends of these chains being connected to the socket cover 14, the incandescent lamp 15, being screwed into the end of a socket within said cover.

The socket cover is suspended by a chain 16, depending from a canopy 17, which is secured to a ceiling in any suitable manner.

60 The conductor wires (not shown) pass through the canopy 17, are looped through the links of the chain 16, and connect with the lamp socket inside the cover 14, in the ordinary manner.

65 18, indicates a frusto-conical reflector flared upwardly and outwardly and pro-

vided with a frusto-conical skirt or shield 19, flared downwardly, and outwardly, but preferably at a lesser degreee of outward flare than the reflector.

60 The reflector and shield may be made integral as shown in Fig. 4 and of any suitable material, but I prefer to make them of metal and separately, secured together by rivets 20, as shown in Fig. 1, there being provided 65 an annular flange 21, at the bottom of the reflector which fits within the upper end of the shield and through which the rivets pass.

22, denotes a plurality of spaced fingers, (three of these being preferably employed), 70 which are formed of a narrow flat strip of metal, or other suitable material, one end of each of which is secured to the inside of the reflector 18, at its lower part by rivets 23, and extends therefrom in a horizontal line a 75 distance corresponding to the length between the outer edge of the rim and inner surface of the translucent bowl 10, the free end of each finger being bent downwardly at right angles to bear against the inner surface of the bowl 80 as shown in Fig. 1. It will thus be seen that the combined reflector and shield is supported by the translucent bowl 10, the spaced fingers 22, resting upon the top of the rim of the bowl, while their downwardly bent 85 ends bear against the inner surface of the bowl and prevent any lateral movement of the reflector and shield.

The combined reflector and shield may be readily applied to or detached from the fixture without disturbing any parts thereof.

In placing it upon the fixture it is passed over the bowl slightly tipped to one side sufficiently to allow the fingers to clear the rim of the bowl until they are in a position 95 to be seated thereon; while in removing it from the fixture it is only necessary to lift it off the rim and tip it in the same manner as when applying it.

It has been found in practice that the best 100 lighting effect is obtained when the lamp is hung in the relative position shown in Fig. 1, that is above the translucent bowl and surrounded by the reflector. In this position the filament is entirely hidden from 105 view, while the light is directed by the reflector away from the beholder so as to fall upon the ceiling which again re-directs the light in the desired direction, while the light emitted by the translucent bowl is not 110 excessively bright and is confined by the shield, preventing any unpleasant or injurious effect.

upon the eyes of the beholder; in fact, when the inner surface of the shield is coated with white paint or enamel, the light is so blended that the translucent bowl is scarcely perceptible.

6 It will be readily understood that the exterior brightness of the light diffusing bowl 10, may be increased or modified, by simply lowering the lamp more or less.

10 I claim as my invention:

1. A lighting fixture comprising an upwardly flaring reflector and a downwardly flaring reflector joined at their smaller ends to form a single reflecting body, a translucent bowl and incandescent lamp around which the reflecting body is supported in such manner that the bowl is within the lower reflector and the lamp within the upper reflector.

20 2. A lighting fixture comprising a frusto-conical upwardly flaring reflector and a frusto-conical downwardly flaring reflector joined at their smaller ends to form a single reflecting body, a translucent bowl and source of light around which the reflecting body is supported in such manner that the bowl is within the lower reflector and the source of light within the upper reflector.

25 3. In a lighting fixture, the combination of a lamp, a bowl, means for suspending the same, a frusto-conical reflector upwardly flared and a depending frusto-conical shield

outwardly flared, and means for supporting the same upon the bowl.

4. In a lighting fixture, the combination of 35 a lamp and socket therefor, a socket cover, means for suspending the same, a bowl, means for supporting the same in predetermined relation to the lamp, a frusto-conical reflector upwardly flared, a depending 40 frusto-conical shield outwardly flared, and a plurality of attached fingers bearing upon the rim of the bowl and supporting the reflector and shield.

5. In a lighting fixture, the combination of 45 a lamp and socket therefor, a socket cover, means for suspending the same, a bowl, a plurality of clips, each formed of one piece of metal bent into a shape to fit over and under the flange of the bowl with one end extending downwardly into the bowl against its inner surface and having an upwardly turned loop intermediate its ends, chains connected at one end to the said loops and at their other ends to the socket cover, a frusto-conical reflector upwardly flared, a depending 55 frusto-conical shield outwardly flared, and a plurality of attached fingers bearing upon the rim of the bowl and supporting the reflector and shield.

60 Signed by me this 21 day of November 1919.

WILLIAM E. JEROME.
